United States Patent Office

Des. 192,784
Patented May 15, 1962

192,784

SHOE HEEL PROTECTOR

Ira Bradley and Branch B. Ray, both of 3710 Ruthelen St., Los Angeles, Calif.

Filed Aug. 7, 1961, Ser. No. 66,229

Term of patent 14 years

(Cl. D7—5)

FIG 3

We claim:

The ornamental design for a shoe heel protector, substantially as shown.
